United States Patent Office

Des. 186,318

Patented Oct. 13, 1959

186,318

THERMOSTAT FOR COOKING APPLIANCES

Chester H. Wickenberg, Elgin, Ill., assignor to Sunbeam Corporation, Chicago, Ill., a corporation of Illinois

Application October 13, 1958, Serial No. 52,950

Term of patent 14 years

(Cl. D26—13)

Fig. 1 is a top perspective view of a thermostat for cooking appliances, showing my new design;

Fig. 2 is a top plan view;

Fig. 3 is a side elevational view, the opposite side being substantially a mirror image thereof;

Fig. 4 is a front end elevational view;

Fig. 5 is a rear end elevational view; and

Fig. 6 is a bottom plan view thereof.

I claim:

The ornamental design for a thermostat for cooking appliances, as shown and described.
